JULIUS FAHDT, OF KOTZSCHENBRODA, NEAR DRESDEN, GERMANY, ASSIGNOR TO THE FIRM OF JULIUS FAHDT MACHINE FACTORY, OF KOTZSCHENBRODA, NEAR DRESDEN, GERMANY

COMPOUND STEAM ENGINE

Application filed November 25, 1927, Serial No. 235,731, and in Germany December 18, 1926.

This invention relates to a method of steam distribution for alternately working and direct acting compound steam engines and has for its object to positively couple the working pistons of direct acting compound steam engines, which are not mechanically connected by shaft, cranks, and rods, so that the reversals of stroke of the two working pistons do not coincide. This alternating working method of the two compound steam cylinders and their pistons is brought about by the known type of spool-shaped piston of the high pressure cylinder, which constitutes the early control organ of the two piston valve gears of the high and low pressure cylinders, the two piston valve gears being released and adjusted separately from each other at various points of the high pressure piston stroke so that the reversals of stroke of the two working pistons do not coincide at any motion and the reversal of the low pressure piston does not take place in the middle of the high pressure piston stroke but is started during the second half of the stroke.

The steam distributing organs of the high and low pressure cylinders may be double piston valve gears of any known type the adjustment of which is altered by the working steam early controlled by the spool-shaped piston of the high pressure cylinder.

The drawing shows a group of compound steam cylinders and discloses the working method of the invention. Fig. 1 shows the object of the invention, when the high pressure piston is in center position and Fig. 2, when the piston is at its extreme lower position.

From the high pressure cylinder, at both ends of the stroke of its spool-shaped working piston H, two ports 2 and 3 lead to the distributing cylinders 6 and 7 of the high pressure cylinder while two ports 4 and 5 lead to the distributing cylinders 8 and 9 of the low pressure cylinder. Through these openings of the ports 2, 3, 4 and 5 of the valve gear over which the high pressure piston H passes in the high pressure cylinder the working steam of the high pressure cylinder is controlled relative to the distributing cyl-

inders of the high and low pressure steam distributing organs, the opening of only one of the two high and low pressure ports 2 or 3 and 4 or 5 being connected with one of the high pressure cylinder sides 11 or 10 at a time while the opening of the corresponding other port is connected with the cylinder chamber S of the high pressure piston H.

Between the high and low pressure cylinders a receiver A is arranged in the known manner, which serves for receiving the exhaust steam from the high pressure cylinder and for supplying the low pressure cylinder with working steam.

Referring to the drawing (Fig. 1) where the high pressure piston H is in the middle of the stroke and the low pressure piston N shown at the upper end of its stroke the play of the working pistons, and particularly that of the high pressure piston H serving as pre-control organ for the two control gears of the working cylinders, proceeds as follows:

The live steam entering at 12 flows in the known manner under the corresponding recess of the high pressure control organ through the lower high pressure port to the lower high pressure cylinder chamber 10 and causes the high pressure piston H to ascend while the high pressure cylinder space 11 is emptied through the upper high pressure port and the exhaust port 13 towards the receiver A. During its ascent the high pressure piston H opens the low pressure port 5 in the high pressure cylinder chamber 10 while the opening of the other low pressure port 4 previously covered by the upper part of the high pressure piston is now covered by the cylinder chamber S of the high pressure piston H. The working steam passes from the high pressure cylinder space 10 through the low pressure port 5 under the distribution piston of the distributing cylinder 9 in order to push the low pressure control organ up. From the upper distributing cylinder 8 the steam passes through the port 4 to the cylinder chamber S and thence into the open through an opening O in the middle of the stroke in the high pressure cylinder.

The adjustment of the low pressure control

organ is altered and the low pressure piston N begins to descend. The high pressure piston H continues to push upwards until, at the end of its stroke, it causes the working steam to enter from the high pressure cylinder chamber 10 through the high pressure port 3 from the distributing cylinder 7 and to push upwards the high pressure control organ for reversing the high pressure piston H, the control steam passing from the upper distributing cylinder 6 through the port 2 into the cylinder chamber S and thence outside through the opening O.

The adjustment of the high pressure distributing gear is now altered, and the high pressure piston H begins to descend to continue the process in opposite direction (Fig. 2).

The peculiar cycle of the four reversals of stroke, particularly the removal of the reversal of the low pressure piston from the middle of the two reversals of stroke of the two high pressure pistons and closer to the following reversal of stroke of the high pressure pistons, is caused as follows.

The speed of the low pressure piston is influenced by the prevailing receiver pressure, and as the receiver pressure is not lowered instantly when throttling the initial high pressure steam for the purpose of slowing down the machine, the piston speed of the low pressure piston will temporarily be greater than that of the high pressure piston. It is therefore necessary to reverse the low pressure piston not in the middle of the stroke of the high pressure piston but somewhat later to avoid coincidence of the reversals at a greater speed of the low pressure piston and to permit the high pressure piston to work in opposite direction before the low pressure piston has reached the end of its stroke.

By means of this reversal of stroke in compound steam engines provided with direct drive of two pump pistons an uninterrupted flow of steam is produced, because at each reversal of one piston the other is engaged in production, and this advantage is combined with the saving in steam resulting from the compound arrangement.

This method of stroke reversal improves further two-stage compound air pumps working direct or crosswise. As the low pressure steam side is opposite the second pressure stage, the drop in pressure due to expansion on the steam side is unfavorably connected with an increase in pressure on the second stage on the air side so that the low pressure side may not remain superior to the increasing air pressure up to the end of the stroke and therefore not complete its stroke.

On the other hand, by employing the reversal of stroke as described the low pressure cylinder receives during the last half of the stroke the flow from the high pressure cylinder exhaust causing an increase in pressure

in the low pressure piston towards the end of its stroke so that it can complete the latter.

I claim:—

A steam controlling device for alternately working and direct acting compound steam engines whose spool-shaped high pressure piston rhythmically pre-controls both working cylinders comprising a low pressure cylinder, a control organ and two control ports for the said low pressure cylinder, a high pressure cylinder with a piston and a cylinder chamber, the said control ports opening equidistantly from the middle of the stroke into the high pressure cylinder, the high pressure cylinder chamber having an opening in the center of the stroke, and the high pressure piston being of a height adapted to release one of the said control ports on passing the middle of the stroke, the other of the said control ports being simultaneously connected with the cylinder chamber.

In testimony whereof I have affixed my signature.

JULIUS FAHDT.
